X-RAY APPARATUS

Robert J. Stava, East Cleveland, Ohio, assignor to Picker X-Ray Corporation Waite Manufacturing Division, Inc., Cleveland, Ohio, a corporation of Ohio

Application June 1, 1938, Serial No. 211,128

6 Claims. (Cl. 250—79)

This invention relates to X-ray apparatus and more particularly to the mounting or support for the fluoroscopic screen employed when the apparatus is used in fluoroscopy.

5 The invention aims to provide counterbalancing means for the screen unit, characterized by the employment of very simple means for connecting a counterbalancing spring to or disconnecting it from the movable screen member, according to whether said member is used for horizontal fluoroscopy, when a counterbalancing effect is desirable, or for vertical fluoroscopy, when such effect is not desirable.

10 A further object is to provide an improved reusable connection for the counterbalancing spring which is very easily disconnected by a manual operation and which utilizes the counterbalancing spring itself to reestablish the connection when the parts are moved to the proper position.

15 Further objects of the invention are in part obvious and in part will appear more in detail hereinafter.

The invention is an improvement upon that shown, described and claimed in Letters Patent 2,097,095, granted October 26, 1937 to Edwin R. Goldfield et al. for X-ray apparatus.

20 In the drawing, which represents one suitable embodiment of the invention, Fig. 1 is an elevation of the fluoroscopic screen unit and its mounting, in their position when used for horizontal fluoroscopy;

Fig. 2 is a sectional elevation on approximately the line 2—2, Figs. 1 and 3;

25 Fig. 3 is a sectional elevation on approximately the line 3—3, Fig. 2, showing in full lines the arm and counterbalancing spring engaged in operative condition; and

Fig. 4 is a similar view, illustrating the disengaging operation.

30 The fluoroscopic screen unit forming the subject matter of the present invention includes a fluoroscopic screen which is moved by the operator to various positions over the patient in the usual manner. The movable parts may weigh as much as ten or fifteen pounds. Consequently, when the tilting table is horizontal so that the screen is above him it is desirable to 35 counterweight the movable screen parts and relieve the operator of the burden of their weight, but, when the tilting table and the patient are in vertical position with the screen in front of the patient, the counterbalancing effect should be dispensed with because it would then impose

upon the operator a burden equal to the counterbalancing effect.

The present invention provides a counterbalanced screen unit provided with improved releasable means by which the counterbalancing effect may be produced or dispensed with in accordance with whether the apparatus is used in horizontal or in vertical fluoroscopy.

The fluoroscopic screen unit comprises a hollow head or casing 1, a depending hollow cylindrical portion 2 of which, when the screen is being used for horizontal fluoroscopy, as in Fig. 1, is mounted for rotation about a vertical axis in a recess or opening in a suitable support 3, being removably held therein in any suitable manner, such as by screw 4. The support 3 may 10 may be carried by the tilting table (not shown) or may be mounted on a stand or other part separate from the table and at one side thereof, as will be readily understood. Said support 3 15 is capable of adjustment about a horizontal axis, as in said prior patent or application referred to, to bring the axis of said cylindrical portion 2 into either vertical or horizontal position, according to whether the screen is used for horizontal 20 or vertical fluoroscopy, as will be readily understood.

Within the hollow head 1 is pivotally mounted at 5 a base 6 in which is journalled an arm 7 carrying the usual fluoroscopic screen 8. Pivoted base 6 is provided beyond its pivot with a hook-like extension 9 extending through an opening in and beneath the cross bar 10 of a coupling member 11 having lateral projections 12 extending through and moving along inclined 30 slots 13 in the side walls of the casing 1, said member beneath the lateral projections having a cross bar 14 forming a perch for a loop at one end of a tension spring 15, whose other end is looped through the eye of an adjusting screw 16 35 threaded into the lower end of the depending cylindrical base 2. Member 11 is also provided with an upwardly extending finger lever 17 passing through an open slot in the wall of casing 1. The rotatable mounting of the base 2 in support 3 permits the fluoroscopic screen to be swung at will either into position opposite the top of the tilting table, for use in fluoroscopic work, or to a position at one side of the table, when the tube alone is to be used for radiographic 45 work, while the journalling of arm 7 in the base 6 permits the screen to be tilted to various positions and even into a vertical plane, as will be obvious.

Figs. 1 and 3 in full lines illustrate the position 50

of the parts when the screen is opposite the table top and the patient thereon, ready for use in fluoroscopy. Cross bar 10 of coupling member 11 is seated in the hooked portion 9 of the screen supporting arm. Counterbalancing spring 15 is extended and has energy stored therein sufficient to fully counterbalance the weight of the extended arm and the screen 8 supported thereby. Consequently, the table being in horizontal position, the operator can swing the screen about pivot 5 toward and from the table to adapt it to the patient without undue burden or effort.

When the screen is used for vertical fluoroscopy, member 3 is turned so that the axis of the depending casing portion 2 is horizontal. The weight of the movable parts, including arm members 6 and 7 and screen 8, constituting the screen unit, requires no counterbalancing effect. When the parts are moved to said position, with the axis of cylindrical portion 2 horizontal, the energized spring 15 contracts and automatically turns the screen carrying arm to the position shown in full lines, Fig. 4. Pins 12 travel down to the lower ends of the slots 13. When the full line position, Fig. 4, is reached the operator can grasp the finger lever 17 and shift it from the full line to the dotted line position, Fig. 4, thus disengaging cross bar 10 from its seat in the notch of the hooked extension 9. This operation fully disconnects the counterbalancing spring from the screen carrying arm, and the latter may then be returned to the position shown in Fig. 1 and may be manipulated with respect to the patient without any burden by the attendant in overcoming the tension of a counterbalancing spring in so doing. During such manipulation the bar 10 is held by the tension of the counterbalancing spring 15 against the outer surface of the hook 9, spring 15 having a tendency to move said bar into a position in line with the length of the spring. Consequently, whenever it is desired to reestablish connection of the counterbalancing spring to the screen carrying arm, said arm is moved outwardly to the position shown in full lines, Fig. 4, when, automatically, spring 15 will snap the bar 10 into its position seated within the hook 9, restoring the connection and again making the spring effective on the arm for full counterbalancing effect when the member 3 is turned back to position for use of the screen in horizontal fluoroscopy.

This is a very simple construction for the purpose of enabling the spring to be readily disconnected and to be made ineffective, and to also automatically reestablish connection in the ordinary course of manipulation of the parts. The counterbalancing spring not only serves for its usual counterbalancing purpose, but also to maintain the parts connected and to tend to return them to connected position when they have been disconnected, in the manner described. But a single spring is used and no special latch or other device is required.

What I claim is:

65 1. X-ray apparatus, comprising a head, an arm pivoted thereto and carrying a fluoroscopic screen,

a counterbalancing spring secured at one end to said head, a coupling member connected to the other end of said spring, said arm having an open seat to receive said coupling member, and an operating lever connected to said coupling member by means of which it may be disconnected from said arm at the will of the operator.

2. X-ray apparatus, comprising a hollow head provided with guides, an arm pivoted to said head and carrying a fluoroscopic screen, a counterbalancing spring secured at one end to said head, a tilting coupling member connected to the other end of said spring, trunnions on said member slidable in the said guides, and said arm having an open seat to receive said coupling member.

3. X-ray apparatus, comprising a hollow head provided with guides, an arm pivoted to said head and carrying a fluoroscopic screen, a counterbalancing spring secured at one end to said head, a tilting coupling member connected to the other end of said spring, and trunnions on said member slidable in the said guides, said arm having an opening seat to receive said coupling member, and said coupling member having an operating lever by means of which it may be tilted about said trunnions to uncouple it from said arm.

4. X-ray apparatus, comprising a hollow head provided with guides, an arm pivoted therein and carrying a fluoroscopic screen, a counterbalancing spring secured at one end to said head, a tilting coupling member provided with opposed portions, one thereof being connected to the other end of said spring, and trunnions on said member between the said portions thereof and slidable in said guides, said arm having an open seat to receive the other portion of said coupling member, whereby the effect of said spring on one portion of said coupling member always exerts a tendency to reestablish coupled relation between the other portion of said coupling member and said arm when they are uncoupled.

5. X-ray apparatus, comprising a hollow head, an arm pivoted therein and carrying a fluoroscopic screen, a counterbalancing spring secured at one end to said head, a releasable connection between the other end of said spring and said arm, said connection being enclosed within said head, and an operating device for actuating said connection to release or connect the same, said operating device extending from said connection to the outside of said head where it is accessible for operation by the operator.

6. X-ray apparatus, comprising a hollow head, an arm pivoted therein and carrying a fluoroscopic screen, a counterbalancing spring secured at one end to said head, a coupling member enclosed within said head and connected to the other end of said spring, said arm having an open seat to receive said coupling member, and an operating device connected to said coupling member for operating the same, said device extending from said coupling member to the outside of said head where it is accessible for operation by the operator.
